M. DOLIVO-DOBROWOLSKY.
DYNAMOMETER WATTMETER.
APPLICATION FILED AUG. 18, 1910.

1,060,894.

Patented May 6, 1913.

UNITED STATES PATENT OFFICE.

MICHAEL DOLIVO-DOBROWOLSKY, OF WILMERSDORF, GERMANY, ASSIGNOR TO
GENERAL ELECTRIC COMPANY, A CORPORATION OF NEW YORK.

DYNAMOMETER-WATTMETER.

1,060,894.

Specification of Letters Patent.

Patented May 6, 1913.

Application filed August 18, 1910. Serial No. 577,862.

To all whom it may concern:

Be it known that I, MICHAEL DOLIVO-DOBROWOLSKY, a citizen of the Swiss Republic, residing at Wilmersdorf, Germany, have invented certain new and useful Improvements in Dynamometer-Wattmeters, of which the following is a specification.

My invention relates to dynamometer wattmeters and has for its object an improvement in the construction of instruments of this character.

More specifically, the object of my invention is the construction of an electro dynamometer wattmeter which shall be compact and simple, have the greatest possible torque, with the use of as few ampere turns as possible, and shall be adapted for circuits of varying capacities.

For a further understanding of my invention, reference may be had to the accompanying drawing, where—

Figure 1 shows a vertical view, partially in section, of a meter constructed in accordance with my invention; Fig. 2 shows a top view of a portion of the same, certain details being omitted; Fig. 3 shows the connections which I employ; and Fig. 4 shows a vertical view of a portion of the meter.

Referring first to Fig. 1, the meter may be fastened to a suitable base 1. 2 and 3 are magnetic cores, the outer of which is formed as a hollow cylinder and the inner as a solid cylinder, these cores being concentric and spaced apart so as to have an air gap 4 between them. These cores I prefer to construct of a laminated silicon alloy, iron or steel. I prefer to use a silicon alloy of iron or steel or any other suitable material having a high electric resistance so as to decrease the iron losses in the core, for, as is well known, the iron losses in a magnetic core produce a phase displacement between the flux in the core and the current flowing in the coil energizing the same, and, if such losses are large, this phase displacement will be comparatively large. By decreasing the proportion of these losses, the phase displacement may also be decreased and thus the accuracy of the instrument increased. They may be fastened together in any suitable manner. Passing between the cores and so through the air gap and revolving in the same is the voltage coil 5, which may be attached to shafts 6, 6' held in suitable bearings. This coil may be provided

with a suitable pointer and scale in the usual manner, and, as these devices form no portion of my invention, I have not illustrated them. In inductive relation with the movable voltage coil is the stationary current coil 7 which I prefer to construct so that it shall be short circuited and consist of a single turn composed of vertical bars joined at their ends by conductors 8 and 9. Conductor 9 may be inserted in the base and cross piece 8 is preferably made removable. This may be accomplished by unscrewing screws 13 which pass through member 8, as shown in the drawing. The stationary current coil may be insulated from the cores by insulation 10 and the cross piece 8 may have surrounding it insulation 10'. Surrounding cross piece 8, or a portion of the current coil, is the magnetic core 11 having wound about it a third coil 12 which is in inductive relation to it and the stationary coil and hence forms the primary of a transformer, of which the stationary current coil forms the secondary winding. This may be better seen by referring to Fig. 4, which shows a view at right angles to that shown in Fig. 1 of member 8 and coil 12 with insulation 10'. 60 65 70 75 80

Referring now to Fig. 3, which shows the connections I employ, 14 and 15 are conductors supplied from a suitable source and feeding a circuit having translating devices 16, whose energy consumption it is desired to measure. The voltage coil 5 may be connected directly across the mains as shown, or in series with a resistance in the well known manner which I have not illustrated, and the third coil or the primary of the current transformer, of which the stationary current coil forms the secondary is connected in series with one of the conductors 85 90 95 of the circuit, as shown.

In case it be desired to measure circuits of varying capacities, cross piece 8 may be removed and the core and coils surrounding this cross piece replaced by a suitable core 100 and coil having a different number of turns, so that the ratio of transformation between the secondary and the primary of this transformer device may be changed and the current flowing in the stationary short-circuited secondary coil for circuits of widely varying capacity will be of a substantially uniform magnitude. Such substitution will be well understood by those skilled in the art. 105 110

While I have described a preferred embodiment of my invention, I do not limit myself to this embodiment but seek in the appended claims to cover all embodiments which will be obvious to those skilled in the art and will not depart from the spirit of my invention.

What I claim as new and desire to secure by Letters Patent of the United States,

10 is:—

1. An electro dynamometer wattmeter comprising in combination a movable voltage coil, a stationary short circuited current coil in inductive relation therewith, a 15 magnetic core surrounding a portion of the current coil, a third coil in inductive relation with the core and the current coil, and means permitting the removal of the core and the third coil from the current coil.
- 20 2. An electro dynamometer comprising in combination two concentric cores of magnetic material spaced apart, a movable coil passing between the cores, a stationary short circuited coil in inductive relation to the movable coil and the cores, and a third coil in inductive relation to the short circuited coil.
- 25 3. An electro dynamometer wattmeter comprising in combination two concentric

cores of magnetic material spaced apart, a 30 voltage coil movable between the cores, a stationary current coil comprising a single short circuited turn in inductive relation to the cores and the voltage coil, a magnetic core surrounding a portion of the current coil in inductive relation thereto, and a third coil in inductive relation with said core and the current coil.

4. An electro dynamometer wattmeter comprising in combination two concentric 40 cores composed of magnetic material of high electric resistance spaced apart, a voltage coil movable between the cores, a stationary current coil comprising a single short circuited turn in inductive relation to the cores 45 and the voltage coil, a core surrounding a portion of the current coil, a third coil surrounding said core in inductive relation to it and the current coil and means permitting the removal of said core and coil from the 50 current coil.

In witness whereof, I have hereunto set my hand this 6th August, 1910.

MICHAEL DOLIVO-DOBROWOLSKY.
